CLAIM

The ornamental design for a case for electronic appliances, as shown and described.

DESCRIPTION

FIG. 1 is a top perspective view of a case for electronic appliances showing the new design.

FIG. 2 is a bottom perspective view thereof.

FIG. 3 is a front view thereof.

FIG. 4 is a back view thereof.

FIG. 5 is a left view thereof.

FIG. 6 is a right view thereof.

FIG. 7 is top view thereof.

FIG. 8 is a bottom view thereof.

FIG. 9 is a top perspective view of the case for electronic appliances shown in an alternate open configuration.

FIG. 10 is a bottom perspective view thereof.

FIG. 11 is a front view thereof.

FIG. 12 is a back view thereof.

FIG. 13 is a left view thereof.

FIG. 14 is a right view thereof.

FIG. 15 is a top view thereof; and,

FIG. 16 is a bottom view thereof.

The features shown in broken lines depict portions of the case for electronic appliances that form no part of the claimed design.
